UNITED STATES PATENT OFFICE.

CLIFFORD NORTON, OF NEW YORK, N. Y., ASSIGNOR TO GRAHAM & NORTON COMPANY,
OF NEW YORK, N. Y., A CORPORATION OF DELAWARE.

ELECTROMECHANICAL INTERLOCK FOR ELEVATORS.

Application filed August 2, 1923. Serial No. 655,175.

To all whom it may concern:

Be it known that I, CLIFFORD NORTON, a citizen of the United States, and a resident of New York, in the county of New York and State of New York, have invented certain new and useful Improvements in Electromechanical Interlocks for Elevators, of which the following is a specification.

My invention relates to a door closing and opening apparatus of the class wherein a pair of toggle arms or levers or other devices are employed for moving a door such as an elevator door or elevator well door from open to closed position and vice versa by the use of applied manual or other power.

The object of my present invention is to provide for a door operating apparatus of the character indicated a simple and effective electromechanical interlock whereby the operation of the car by the electric or similar power is rendered impossible so long as door opening and closing mechanism is in position to permit ingress and egress through the door opening.

To this end my invention consists essentially in the combination with the door closing and opening mechanism of a latch which serves to lock a member thereof in the door closing position and an electric circuit breaker and closer controlling the application of the electric power to the elevator in any of the well known ways and operating in such a manner that when the catch is lifted for the purpose of releasing said member to permit the same to be operated and to open the door, the electric system or circuit will be rendered inoperative and will remain inoperative so that the car cannot be moved until the catch is restored to a position for locking said member in the door closing position.

My present invention consists also in the particular combinations of devices and details of construction hereinafter more particularly described and then specified in the claims.

In the drawings:

Fig. 1 is a general side elevation of an apparatus embodying my invention.

Fig. 2 is an edge view of the same.

Fig. 3 shows in detail the toggle arm catch and the connected switch in enlarged view.

Fig. 4 illustrates a modification in the means for connecting the toggle arm catch to the electric switch.

Fig. 5 shows a device which may be employed for operating the catch in a push-button system of elevator control.

1 indicates an elevator well door which may be of the sliding type. The door closing and opening mechanism is here shown as of the toggle arm type although the invention may be applied likewise to other forms employing a lever or levers for imparting movement to the door. One of said arms 2 is pivoted, as indicated, to the sliding door and the other 2' is pivoted at a fixed bracket or abutment secured to a studding or wall of the elevator shaft or otherwise fixedly supported. The toggle arm system or levers thereof are pivotally connected together as at 3 and as well understood in the art. Said toggle may be operated as also well understood in the art by a handle 4 or by a cylinder 5 or in any other desired manner. In the case of the latter device, the power may be pneumatic or other power or may be power stored in a spring acting on a piston within the cylinder 5 when the handle 4 or other device is used to apply power in the opening of the door.

The device here shown is of the general type described in the Norton Patent No. 1,124,941, dated January 12, 1915, embodying in addition to the spring a suitable liquid check or dashpot at its lower end which comes into action when the spring operates to close the door. The device 5, however, is to be understood as being merely illustrative of any means for applying pneumatic or other power in the opening or closing movement or both, said device being suitably connected to the lever arm 2' by a pivotal or other connection.

Applied to an arm of the toggle as for instance arm 2', is a catch or locking device indicated at 7 and shown for illustration as a latch or lever. Said latch is pivotally mounted at 8 on a fixed support such as the wall of the elevator shaft or studding and at its free end is a locking shoulder 7' adapted to rest upon and lockingly engage a stud or arm 8' carried by the toggle arm 2'. Obviously said latch operates to pre-

5 vent the arm 2' from swinging upward in the arc of a circle which it must do in order that the toggle may carry the door 1 back from the closed position indicated in Fig. 6 1 and in the direction of the arrow 9 in order to open the door. Gravity or a spring 10 may serve to normally hold or assist in holding the locking catch 7 in the normal position shown. When, however, said 15 catch is raised to free the arm 2' the latter may swing upwardly in the door opening movement.

29 indicates the casing of an interlocking switch of any desired type or form applied 15 to act on an operating or controlling circuit of the motive power by which the car is moved in such a manner that in one position of the switch the car may be moved by manual or automatic control while in the 20 other position the apparatus is rendered inoperative to move the car. The manner of connecting a switch having this function into the circuits is well understood in the art and need not be further particularly described. Circuit wires for said switch are indicated at 10 10'. The operating member of said switch, which member may be of any desired form or form suited to the type of switch employed, is indicated at 12.

25 In the present instance I have shown my invention as carried out by the use of a type of switch substantially like that described in my application for patent filed February 2nd 1923, Serial No. 616,485, and having two 30 spring-pressed circuit closing members 11 11' which normally tend to engage one another and close the circuit of 10 10'. A reciprocating bar or block of insulating material like "bakelite" or other suitable material 35 constitutes the operating member 12 and is mounted in position between the circuit closing arms 11 11' and is adapted to be forced between and separate said arms to break the circuit. In the normal position 40 or circuit closing position said block or bar 12 occupies the position indicated in full lines in Fig. 3. Said block or other operating member of the switch is attached to link 12' and said link is in turn joined to the 45 latch or an arm 14 extending therefrom by means adjustable if desired longitudinally to adjust the throw of the parts as indicated at 13. When it is desired to operate the toggle arm to open the door it is necessary 50 to lift the latch 7 and in so doing the switch is operated to break the interlocking control circuit, thereby stopping or rendering it impossible to further operate the car by its motive power.

55 The operating device for lifting the catch or latch and at the same time operating the switch is typified by the bar or rod 6 suitably guided and working vertically.

60 Said lifting bar which may be operated by any desired means is operatively connected

6 with the latch and switch by means of a toe or head arranged beneath the latch to engage and lift the latch and at the same time operate a switch when the rod is lifted or by other suitable means.

65 In applying my invention to a system wherein the car is operated under the control of an attendant on the car who applies or cuts off the motive power and manipulates the well door operating or control mechanism, said bar may be actuated by cam 15 or other device suitably mounted on the car and adapted to be thrust sidewise by the operator by means of a pedal or other means, against the vertical arm of a bell-crank lever 17 whose other arm is connected to the lifting bar 6.

70 The cam 15 may be, as shown, of the form and extent usually employed and have a cam or engaging surface of sufficient length 75 in a vertical direction to permit it to operate upon the bell-crank lever or other device operatively connected with the latch, when the car floor 16 is within a certain limited distance above or below the landing floor, so that it is not necessary in the operation of the car to bring the car floor and landing floor to exactly the same level before the landing door can be opened. Outside of the limits determined by the length of the engaging surface 15 the bell-crank 17 cannot be operated for the purpose of placing the door operating mechanism in operative condition to open said door.

75 In Fig. 1 the car is shown at the landing with the cam in position ready to lift the latch when the cam is thrust sidewise in the usual way. As soon as the latch is lifted the toggle may be operated, thus swinging the arm 2' upwardly and causing the well door to move in the direction of the arrow 9. The pin or dog 8 then moves under the latch while at the same time the arm acts upon the circuit breaker so as to render the motive power mechanism or controlling devices therefor inoperative electrically to move the car away from the landing. Further movement of the car can only take place after the switch is permitted to resume its normal position by closing the door and thus restore the circuit or circuits to normal condition. The latch remains lifted while the door is open owing to the fact that it rides upon the dog 8 and sustains the switch in the interlocking condition until the arm 2' is thrown down sufficiently to close the door. On completion of this movement the latch operatively engages the dog and locks the operating arm 2' in the position indicated in the Fig. 1.

80 At this time and not until this time can the operating member 12 of the switch reach position such that the interlocking switch would close the circuit. When the door is thus locked the motive power may be con-

trolled or applied over the electric controlling or operating circuits in the usual or any desired way.

The toggle arms or levers shown, when they are straight, obviously lock the door against movement by any extraneous force applied to the door itself while, moreover, locking of the door under normal conditions is further insured by the latch which engages an arm of the toggle in the locking position thereof.

In connection with the devices on the car for operating the latch an interlocking bar 18 may be employed co-operating with the usual electric controller 30 in such way that the controller must be brought to neutral position or position for cutting off the motive power before the cam 15 can be operated by the pedal. Such interlocking bar 18 is properly connected with the pedal-operated lever 19 which in turn, by the horizontal bar 20, actuates the cam 15 when the pedal is depressed. The spring for returning said pedal-operated parts to normal position or inoperative position of the cam is indicated at 21. When the pedal is operated after the controller has been thrown to neutral position to stop the car, the locking bar 18 enters a locking notch in a cam indicated in dotted lines, the entry of the bar permitting the cam to be thrown over and to thus act. In previous constructions of apparatus a "mechanical interlock" is employed which, in its normal position, locks the door against movement until, being actuated by the cam, the lock is operated so as to free the door. Said mechanical interlock is also so constructed that it holds the cam in projected position so long as the door is open and thus holds the locking bar 18 engaged with the controller so that said controller may not be operated. But after the door has been again closed the mechanical interlock is freed to free the cam and allow it to return to normal position, thus unlocking the controller so that the car may be moved.

By the use of my present invention the use of the "mechanical interlock" engaging the cam and the door may if desired be dispensed with.

The operation of the apparatus, when employed in connection with the locking bar 18, is as follows:

When the car is stopped at the landing by the operation of the controller 30, said controller is in position to permit the locking bar 18 to be lifted into the notch by the operation of the pedal; but said pedal cannot be operated to operate the cam until said controller has been placed in such neutral or "stop" position and the car is thus brought to rest. When, and only when, the car is brought to rest opposite the landing the operation of the cam 15 will free the well door operating mechanism from the

locking action of the latch 7 at which time, and at the same time, the interlocking electric switch 29 will be actuated. By the action of the interlocking switch and as already described, further operation of the car by means of the controller 30 is rendered impossible until the interlocking switch is restored to normal position. Hence, although the release of pressure on the pedal may allow the cam 15 and the bar 18 to resume normal position and free the controller 30, the same is kept electrically inoperative, the interlocking switch 29 in this phase of the operations acting as a substitute for the mechanical interlock before referred to which mechanically holds the cam extended until the door is restored to closed position.

In my present construction the closing of the door frees the latch 7 to allow the interlocking switch 29 to resume normal position, whereupon the controller 30 becomes electrically operative in the usual way.

Fig. 4 illustrates a modification in the manner of operating the interlocking switch from the latch 7 when said switch is a master switch or one common to a number of elevator doors as described in my application for patent filed July 7th 1923, Serial No. 650,043. In this figure 22 indicates the line extending vertically past the several floors and operatively connected with the switch at the head of the elevator shaft, or otherwise located, said line being provided for each landing with a button or lateral projection 23 in position to be engaged by a device operatively connected with the latch. In the present instance the latch 7 has an arm 24 terminating above or below the button 23 in a yoke or eye so that, when the latch is lifted, a pull is exerted on the line 22 and the interlocking electric switch is operated rendering it impossible to operate the car so long as the latch is lifted from position for locking the operating arm of the door. The single interlocking switch can be operated in this way from the latch for the door operating mechanism at any floor.

My invention may likewise be readily applied to any push-button system organized in a manner well understood in the art to automatically stop the car when the floor selected by a particular push-button is reached. An example of this is illustrated in Fig. 5 wherein an operating cam for the latch operating bar 6 is brought into action through the interruption of a circuit which is caused to take place automatically when the selected floor is reached by the car. Inasmuch as circuits and arrangements of circuits for this purpose are well understood in the art, I have shown merely the devices connected immediately with the cam for causing the same to operate on the lifting

bar 6. In this figure 25 indicates an electric motor carried by the car. Said motor is energized so long as the circuits are in condition to move the car and operates a drum 26 which winds up a cord or chain connected with the cam and with a rod 27 that, in the winding movement, stores power in a compressible spring 28 as clearly indicated. While the motor is energized the cam is held 10 by the motor in inoperative position. When the car reaches the floor, automatic change of circuit condition, resulting from the operation of the push-button system de-energizes said motor and the spring 28 then operates to throw the cam 15 and bar 6 and thereby disengaging the latch 7 so that the door may be then opened. This action, as before, results in the throwing of the interlocking switch before described so that motive power for the elevator is no longer applied and cannot be applied until the door operating mechanism is restored to position for permitting the latch 7 to drop to normal position or position where the door opening 20 and closing devices are located. When, however, it is desired to move the car away from the floor the motor 25 becomes energized, thus withdrawing the cam 15 and permitting the latch 7 and connected switch 30 to resume their normal position, the door operating mechanism being then and thereafter locked until again freed by the automatic operation of the latch.

As will be seen, the office of the electric motor 25 which is normally energized while the car is moving, is to hold the cam or other operating device in inoperative position by electromagnetic action and to free the same for operation by the spring or other device when the car is at the selected landing, through interruption of the charging circuit for the electromagnet in the operation of the push-button system. Other electromagnetic devices might be employed 45 in a similar way in place of the motor 25.

The combination of electro-magnetic means on the car as shown in Fig. 5 co-operating with the elevator well door closing and opening mechanism, latch and power controlling switch, is not made the subject of specific claims herein since it forms the subject of a separate application filed as a division of the present case.

What I claim as my invention is:—

55 1. The combination with a door, of mechanism including a movable member for moving said door to open or closed position, a latch adapted to lock said movable member against movement when said door is in closed position, and a power controlling switch operatively associated with said latch, and means for simultaneously controlling said latch and switch.

60 2. The combination with a door, of a door closing and opening mechanism comprising

70 a pair of pivotally connected arms one of which is pivoted to the door and the other to a fixed bracket or abutment, a latch engaging one of said arms and adapted to hold the same in door closing position, and a power controlling switch connected to said latch and adapted to change the condition of an electric circuit when the latch is moved to free the arm.

75 3. The combination with a door closing and opening mechanism comprising toggle arms or levers pivotally connected together of a latch engaging the fixedly mounted member and a power controlling switch operatively connected with said latch.

80 4. The combination with a door opening and closing mechanism, of a latch engaging a member thereof to hold it against movement and in the closed position of the door, a power controlling electric switch operatively connected to the latch, an actuating rod adapted to engage the latch to free the mechanism and means upon the car for operating said rod or bar at the landing.

85 5. The combination with a door opening and closing mechanism including a movable door operating member, of a latch engaging said member to hold it against movement and in the closed position of the door, a power controlling electric switch connected to said latch, an electric controller on the car, a lock therefor, and means upon the car for operating said lock and said latch simultaneously.

90 6. The combination of an elevator well door, a lock therefor, an electric switch, an elevator car provided with an electric controller, and means upon the car interlocked with said controller for operating said locking means and switch simultaneously when the car has been brought to rest at a landing by the operation of the controller.

95 7. The combination with an elevator well door and operating mechanism therefor, of a latch normally locking the same, an electric switch connected to said latch, actuating means on the car for operating said latch when the car is at a landing, an electric controller on the car and means holding said actuating means out of action while the controller is in position to cause the car to move.

100 8. The combination with a door and an operating lever therefor for moving the same to open or closed position, of a pivoted latch engaging and locking said lever in door closing position, adapted to ride thereon when the lever is moved away from such position to open the door, and a power controlling electric switch operatively connected with the latch.

105 9. The combination with a door, of a pair of toggle arms pivotally connected and adapted in normal position to lock the door against movement, a latch engaging one of

said arms and adapted to lock the toggle system and means for operating the latch to permit the door to be moved.

10. The combination with a door and the opening and closing mechanism therefor, of a power controlling electric switch, a latch adapted to lock a member of said mechanism in the closed position of the door and

means for acting simultaneously on said latch and switch operable from the elevator car when the car is at a landing.

Signed at New York, in the county of New York and State of New York, this 1st day of August A. D. 1923.

CLIFFORD NORTON.
